UNITED STATES PATENT OFFICE.

LOUIS BERNHARD, OF BOSTON, MASSACHUSETTS.

FIRE BOX.

Application filed April 28, 1923. Serial No. 635,347.

The principal object of my invention is to provide a construction for use with boilers or Dutch ovens, for example, or for other uses such that the fire bricks will be protected from burning and will not scale off by burning or clinking. Other objects will be pointed out below.

A feature of my invention is a wall of material, preferably high temperature cement, to protect the bricks against heat.

Another feature is a particular relative location of the fire bricks to furnish a grip to hold said wall in place.

Another feature is that in one course the bricks are reversely arranged with relation to the corresponding bricks of an adjacent course.

Other features will be pointed out below.

In the drawing—

20 Figure 1 is a plan of a fire box setting embodying my invention;

Figure 2 is an elevation of a relieving arch extending lengthwise of, and above, the setting; and

25 Figure 3 is a section on line 3—3 of Figure 1.

The outer walls of the setting may be made of red brick A and above the fire box is a relieving arch B which may, if desired, extend the entire length of the chamber D for the boiler, for example.

In Figure 1 the fire bricks E and fire bricks F form one course and are shown in full lines. The bricks E are laid parallel but their long faces are at an angle to the chamber so that they form pockets such as e for a purpose to be described below. The bricks F are laid parallel to each other and their long faces are also at an angle to the chamber but reversely with relation to the bricks E and they also form pockets such as f.

In the next course below there are bricks G parallel to each other and to bricks F and in this course also are bricks H parallel to each other and to bricks E, there being pockets g and pockets h similar to pockets e and f. It will be observed that pocket e is located between the brick G in the course below and the brick G in the course above and the other pockets are similarly located, the spaces e' however being vertically continuous, while there is no continuous vertical space where the pockets f and h are located.

55 Suitable binders J are provided to hold the courses together.

At the inside ends of the bricks E and G I apply some suitable heat resisting material K, preferably high temperature cement, and this completely fills the pockets e and g and the spaces e', which thus furnish a large and substantial gripping area for the cement which preferably extends inwardly slightly from the inner corners of the bricks as clearly shown in Figure 3.

I also preferably fill the pockets f and h with said cement in order to protect the portions of the bricks adjacent to those pockets.

It will be understood that I may have as many courses as desired but adjacent courses will have relatively reverse arrangement, that is to say, any particular brick in one course will be at a different angle to said chamber from the angle of the brick immediately above or below it.

What I claim is:

1. A fire box comprising a chamber; a course of bricks formed of two sets, one set having its bricks parallel to each other and at an angle to said chamber and the other set having its bricks parallel to each other and at an angle to said chamber different from the angle of the first-mentioned set; and heat resisting material between said two sets.

2. A fire box comprising a chamber; one course of bricks formed of two sets; one set having its bricks parallel to each other and at an angle to said chamber and the other set having its bricks parallel to each other and at an angle to said chamber different from the angle of the first-mentioned set; heat resisting material between said two sets; a second course of bricks adjacent the first course and formed of two sets, one set having its bricks parallel to each other and at an angle to said chamber but reversely with relation to the adjacent bricks of the first-mentioned course and the other set having its bricks parallel to each other and at an angle to said chamber different from the angle of the first-mentioned set of said other course but reversely with relation to the adjacent bricks of the first-mentioned course; and heat resisting material between the two sets of said second course.

3. A fire box comprising a chamber; one course of bricks formed of two sets; one set having its bricks parallel to each other and at an angle to said chamber and the other set having its bricks parallel to each other and at an angle to said chamber different

11. On the angle of the first mentioned set; heat-resisting material between said two sets; a second course of bricks adjacent the first course and formed of two sets, one set 5 having its bricks parallel to each other and at an angle to said chamber but reversely with relation to the adjacent bricks of the first-mentioned course and the other set having its bricks parallel to each other and 10 at an angle to said chamber different from the angle of the first-mentioned set of said other course but reversely with relation to the adjacent bricks of the first-mentioned course; and heat-resisting material between 15 the two sets of said second course; the inner sets of said courses forming pockets adjacent said chamber; and high temperature cement filling said pockets and extending inwardly toward said chamber beyond the inner corners of said bricks to form a wall held in place by that portion of the cement 20 which is in said pockets.

4. A fire box comprising a chamber; one course of bricks formed of two sets, one set 25 having its bricks parallel to each other and at an angle to said chamber and the other set having its bricks parallel to each other and at an angle to said chamber different from the angle of the first-mentioned set; a second course of bricks adjacent the first course and 30 formed of two sets, one set having its bricks parallel to each other and at an angle to said chamber but reversely with relation to the adjacent bricks of the first-mentioned course and the other set having its bricks 35 parallel to each other and at an angle to said chamber different from the angle of the first-mentioned set of said other course but reversely with relation to the adjacent 40 bricks of the first-mentioned course; the bricks of one course overlapping the bricks of the other course so as to break continuous air spaces between said course.

LOUIS BERNHARD.
